SWIMMING GEAR

Ida Florence Redwine, Waltham, Mass.

Application July 2, 1938, Serial No. 217,162

5 Claims. (Cl. 9—17)

This invention relates to improvements in swimming gear.

More particularly it provides an inflatable device with means for arranging it in the neck region below the back of a person's head, as an aid in maintaining a bather's head above the surface of the water.

It has been proposed heretofore to make bathing caps with inflatable portions built into the cap for buoyancy. But all such, so far as I am aware, have the inherent evil that the air pressure within the inflated portions of the cap continually presses on the wearer's head, with consequent discomfort, and, in many cases, with continuing tendency of the cap to thrust itself off the head. If this is opposed by a strap fastening under the chin, that strap is kept uncomfortably tight by the air pressure in the cap working against it.

The present invention provides a buoyant support which may be secured to the head but whose inflation does not put discomforting pressure on the head or on any other part of the wearer's person.

This invention provides both secure attachment of the buoyancy means under the head, and buoyant support of the head, without the buoyant lift, or the air pressure, tending to remove the device from the head.

Still another feature is that the buoyant element with its head-engaging carrier can be worn on a person's head, with an ordinary bathing cap; or it may be built as an addition to a bathing cap, with the cap serving the function of the head-engaging carrier.

It is, moreover, an important feature that the invention may be made of inexpensive flexible materials which permit of the folding of the device into a compact and small parcel.

The device as a whole can serve effectively and beneficially as an aid in keeping one's head above water, both as an assurance of safety in bathing, and as an aid in learning to swim.

The invention attains these objects and results by shaping and mounting an inflatable device as an appendage or flap depending from a head-fitting mesh or cap, so as to lie across the back of a person's neck. The device may be permanently or detachably secured to the head engaging device; and it may be secured to the mesh or cap in a manner which permits it to rise as on a hinge to lie against the back of the head; or stiff bones may extend down from the cap along the neck, to maintain it in position across the neck where it will be likely to be submerged and so always to contribute buoyancy to the wearer whenever the

head is at water level. Or, tie strings may extend from the flap, to be tied under the chin, or to cross and tie to the shoulder straps of a bathing suit.

Any well known means, with or without a valve, may be provided for inflating the flap device to a practicable size.

It is intended that the patent shall cover, by suitable expression in the appended claims, whatever features of patentable novelty exist in the invention disclosed.

In the accompanying drawing:

Figure 1 is a perspective showing of inflated headgear, embodying features of the invention, as when in use;

Figure 2 is an elevation of a headgear similar to that of Figure 1 with the buoyancy device deflated and secured to a strap band all along its top edge;

Figure 3 is an elevation of a fragment of the device of Figure 2, looking at the rear side thereof;

Figure 4 is a view similar to Figure 2 showing stiffening means for preventing the buoyancy device from rising from its position at the neck;

Figure 5 is an elevation in medial section through one of the stiffeners; and

Figure 6 is a perspective of a modified form of device, looking at the rear side thereof.

Referring to the drawing, the invention is illustrated as embodied in swimming gear comprising a mesh or skeleton cap of straps 10 and 12, of which the strap 10 is a circular band, for extending around the head, and the straps 12 have their ends secured to the strap 10 on opposite sides of the head, with their respective curvatures adapted to extend over the crown of the head. Although this skeleton structure at present is preferred, it will be obvious that any head piece which fits with suitable security might be employed as a carrier for the buoyancy device 14 now to be described. Whether a full cap be used, as an ordinary rubber bathing cap, or the skeleton cap above noted, there will be the strap 10 or its equivalent passing around the brow and under the back of the head to constitute a securely held band, which can make the buoyant element remain under the back of the neck and head.

In use, the headgear will be fitted on the head with the flap-bag 14 at the back of the neck. The bag may be inflated through any suitable mouth tube 16, which may then be folded and secured upon itself to prevent escape of air; or an automatic valve may control the inflating and deflating.

Figure 1 shows bag 14 of two sheets of rubberized fabric inflated, joined at the edges, and

serving as a buoyancy element engaged under the head, across the back of the neck of the bather. The air capacity of bag 14 may vary at choice of the maker, but is represented large enough to constitute a substantial aid to the maintenance of the head and face above the surface of the water.

Figure 4 illustrates how the flap 14' may be stiffly held down close to the neck by extensions 18 of two of the straps 12, resisting its buoyant tendency to turn upward to the surface, the buoyancy gained from it by the user being greater when it is submerged.

These stiffeners may be thin, stiff bars of steel 15 suitably curved to avoid discomfort of a person's neck or shoulders, and covered by a suitable fabric 21 which, if desired, may be slightly padded.

Without stiffeners, tie-strings 19 may extend from the flap 14, to be tied under the chin, or to 20 be crossed in front and tied to the shoulder straps of a bathing suit, to hold the inflated flap down against the neck. These constitute a safeguard against loss of the buoyant element if the head-piece should be washed off.

Figure 6 shows a skeleton cap which may be made of suitably heavy rubber, such as the rubber customarily used for bathing caps. In the drawing the cap is spread sideways to show the two male snap elements 20 on opposite sides, 30 over which a female snap element 22 on a buckle element 24 at each end of a chin strap 26 may engage, for securing the cap on the head.

In this form, the buoyance flap 28 is secured to the band 30 by a flexible hinge piece 32 which extends a little beyond the edge of band 30, as indicated at 34. The hinge 32 may be integral with flap 28 or may be a separate piece of heavier and stronger flexible material secured to flap 28. By making the hinge connection relatively narrow as represented, there is less tendency for the flap to be torn away from the cap by the forces which are effective on the inflated flap in use. Also it facilitates the placing of a regular bathing cap over the skeleton cap, when desired. 40 because it permits the lower edge of the bathing cap to fit tightly over the secured portion of hinge, with the slight projecting part 34, and the flap 28, free of the bathing cap. The inflated flap may be left free to float at or near the surface of water, or may be tied against the neck as suggested in regard to flap 14.

It will be understood that the statements regarding utility and comfort of this buoyant element for persons who are not accomplished

swimmers does not imply that it is a life saving device. The buoyant volume illustrated is to learners and bathers helpful and encouraging as an aid to flotation but is not enough to be controlling as a safety device.

I claim as my invention:

1. Swimming gear comprising an inflatable buoyancy element; means adapted to fit on a person's head for securing said element at the back of that person's neck; said buoyancy element having extent in direction crosswise of the neck considerably exceeding the width of the back of a person's neck, with connection to said head-fitting means at a mid-location in its said crosswise extent, from which connection portions of the element project further in the crosswise direction and are free from direct attachment to the head-fitting means. 10

2. Swimming gear as in claim 1, wherein the said buoyancy element, when inflated, has a 20 shape which is prolate on horizontal axis; the said first mentioned connection being a hinge connection to said head-fitting means at a location which will be at the lower back of the head of the person wearing the swimming gear. 25

3. Swimming gear, as in claim 1, wherein the said buoyancy element, when inflated, has a 30 shape which is prolate on horizontal axis; and the connection first mentioned is a piece of flexible sheet material projecting between the buoyancy element and said head-fitting means at a location which will be at the lower back of the head of the person wearing the swimming gear.

4. Swimming gear comprising an inflatable buoyancy element; means adapted to fit on a 35 person's head for securing said element at the back of a person's neck; and a relatively narrow hinge connection between the head-fitting means and the buoyancy element permitting free swinging of the said element toward and away from 40 the head of a wearer of the swim gear.

5. Swimming gear comprising an inflatable buoyancy element; means adapted to fit on a 45 person's head for securing said element at the back of that person's neck; said buoyancy element having extent in direction crosswise of the neck considerably exceeding the width of the back of a person's neck, and having its greatest vertical extent in the mid-region behind the person's neck, with connection to said head-fitting 50 means at the region of its said greatest vertical extent.

IDA FLORENCE REDWINE.
